OTHER PUBLICATIONS

Mexican Office Action dated Oct. 25, 2019 for Mexican Patent Application No. MX/f/2018/002415, a counterpart of U.S. Pat. No. D. 871,776, 4 pages.

Primary Examiner — Karen S Acker

(74) Attorney, Agent, or Firm — Lee & Hayes, P.C.

(57) **CLAIM**

The ornamental design for a paper product, as shown and described.

DESCRIPTION

The sole FIGURE is a plan view of a paper product. The broken lines surrounding the figure depict the boundaries of the claim and form no part thereof. The broken lines within the boundary depict portions of the paper product that form no part of the claimed design.

1 Claim, 1 Drawing Sheet
